(57) **CLAIM**

The ornamental design for dual storage compartment device,
as shown and described.

DESCRIPTION

FIG. 1 is a front perspective view of a dual storage compartment device shown in a closed position;

FIG. 2 is a front elevational view of the dual storage compartment device shown in FIG. 1;

FIG. 3 is a rear elevational view of the dual storage compartment device shown in FIG. 1;

FIG. 4 is a left-side elevational view of the dual storage compartment device shown in FIG. 1;

FIG. 5 is a right-side elevational view of the dual storage compartment device shown in FIG. 1;

FIG. 6 is a top plan view of the dual storage compartment device shown in FIG. 1;

FIG. 7 is a bottom plan view of the dual storage compartment device shown in FIG. 1;

FIG. 8 is a front perspective view of the dual storage compartment device shown in an open position;

FIG. 9 is a front elevational view of the dual storage compartment device shown in FIG. 8;

FIG. 10 is a rear elevational view of the dual storage compartment device shown in FIG. 8;

FIG. 11 is a left-side elevational view of the dual storage compartment device shown in FIG. 8;

FIG. 12 is a right-side elevational view of the dual storage compartment device shown in FIG. 8;

FIG. 13 is a top plan view of the dual storage compartment device shown in FIG. 8; and,

FIG. 14 is a bottom plan view of the dual storage compartment device shown in FIG. 8.

The broken lines shown in the drawings represent portions
of the dual storage compartment device that form no part of
the claimed design.

1 Claim, 10 Drawing Sheets
